UNITED STATES PATENT OFFICE.

GEORGE B. DAVIS, OF DAWSON, YUKON TERRITORY, CANADA.

HOOD FOR PROPELLER-WHEELS.

No. 904,313.

Specification of Letters Patent.

Patented Nov. 17, 1908.

Application filed January 17, 1908. Serial No. 411,212.

To all whom it may concern:

Be it known that I, GEORGE B. DAVIS, a citizen of the United States, residing at Dawson, Yukon Territory, Canada, have invented certain new and useful Improvements in Hoods for Propeller-Wheels; and I do declare the following to be a full, clear, and exact description of the invention, such as will enable others skilled in the art to 10 which it appertains to make and use the same.

This invention relates to improvements in hoods for screw propellers.

The object of the invention is to provide a 15 hood or funnel for propellers whereby the same may be used in shoal water.

With this object in view, the invention consists of certain novel features of construction, combination and arrangement of 20 parts as will be more fully described and particularly pointed out in the appended claims.

In the accompanying drawing, Figure 1 is a side view of the stern end of a boat, 25 showing the application of the invention thereto; Fig. 2 is a similar view, showing the hood in section; and Fig. 3 is a rear end view.

Referring more particularly to the drawings, 1 denotes the hood, which is preferably formed of sheet metal and is adapted to be constructed in any suitable shape, such as cylindrical, half-round, oval, square, triangular and tapering or funnel-shaped, or 30 provided with straight sides, the same being shown in the present instance as being substantially half-round or semi-cylindrical at its outer end and having its sides and lower edges tapering slightly toward the inner 35 end. The hood is adapted to be arranged over the upper side of the propeller wheel and to project rearwardly of the same and also to a slight distance ahead of the wheel beneath the stern end of the boat, as shown. 40 The hood is adjustably supported in position by a vertically disposed supporting bar, 2, arranged in suitable bearings, 3, secured to the stern of the boat, as shown. The lower end of the bar, 2, is bifurcated to form diverging supporting plates, 4, which straddle the upper side of the hood and are pivotally connected thereto at their lower ends.

On the bar, 2, is slidably mounted a collar, 5, which is adapted to be adjustably secured to the bar, 2, by means of a set-screw 6, said collar forming a stop adapted to be

connected with the upper bearing, 3, on the stern of the boat, whereby the hood is adjustably supported and held in position over the propeller wheel. On the upper side of 60 the hood, adjacent to the rear end thereof, is formed a centrally disposed upwardly projecting fin, 7, with which is pivotally connected the lower end of an inclined brace bar, 8, the upper inner end of which is pivotally connected to an apertured lug, 9, on the collar 5. The brace bar 8 is adapted to steady and steer the rear end of the hood, and together with the fin 7 is adapted to hold the hood in line with the center of the propeller wheel when drawn through the water. By loosening the set screw, 6, in the collar, 5, the supporting bar, 2, may be raised or lowered to adjust the hood to the desired position over the propeller wheel. 75

If desired, the hood may be connected with the rudder so that it will aid in the steering of the vessel and the operation of the wheel by taking water from under the vessel or from either side. 80

Having thus fully described my invention, what I claim as new and desire to secure by Letters-Patent, is:

1. In a hood for propeller wheels, a supporting bar having a pivotal engagement at 85 its lower end with the hood, and means connected to said supporting bar and hood to steady the rear end of the latter, substantially as described.

2. In a hood for propeller wheels, a supporting bar pivotally connected at its lower end to said hood, means to adjustably secure the bar to the end of the vessel, a brace pivotally connected at one end to the outer end of the hood, and means whereby the opposite 95 end of said brace is connected to said supporting bar, substantially as described. 90

3. A hood for propeller wheels adapted to be arranged over the same, a supporting bar bifurcated at its lower end and adapted to be 100 pivotally connected to said hood adjacent to its inner end, a stop collar arranged on said bar to adjustably secure the same to the stern of the vessel, and means to support and guide the outer end of the hood, substantially as described. 105

4. A hood for propeller wheels adapted to be arranged over the same, a supporting bar bifurcated at its lower end and adapted to be pivotally connected to said hood adjacent to its inner end, a stop collar arranged on 110 said bar to adjustably secure the same to the

stern of a vessel, a centrally disposed longitudinal upwardly projecting fin arranged on the upper side of said hood, and an obliquely disposed brace adapted to connect said fin with said stop collar, substantially as described.

5. A hood for propeller wheels comprising a longitudinally disposed curved plate, the sides of which taper toward its inner end, a 10 supporting bar having a bifurcated lower end pivotally connected to said hood adjacent to its inner end, bearings arranged on the stern of the vessel to receive said bar, a stop collar arranged on the latter above said

bearings, a set screw to hold said collar in 15 adjusted position on said bar, a centrally disposed longitudinal upwardly projecting fin formed on the rear portion of said hood, and an obliquely disposed brace adapted to connect said fin with said collar, substantially 20 as described.

In testimony whereof I have hereunto set my hand in presence of two subscribing witnesses.

GEORGE B. DAVIS.
